UNITED STATES PATENT OFFICE.

GEORGE H. GILMAN, OF CLAREMONT, NEW HAMPSHIRE, ASSIGNOR, BY MESNE ASSIGNMENTS, TO SULLIVAN MACHINERY COMPANY, OF BOSTON, MASSACHUSETTS, A CORPORATION OF MASSACHUSETTS.

ROCK-DRILL.

1,250,931.

Specification of Letters Patent. Patented Dec. 18, 1917.

Original application filed July 6, 1911, Serial No. 637,100. Divided and this application filed January 15, 1912. Serial No. 671,376.

To all whom it may concern:

Be it known that I, GEORGE H. GILMAN, a citizen of the United States, and a resident of Claremont, county of Sullivan, State of New Hampshire, (whose post-office address is Claremont, New Hampshire,) have invented an Improvement in Rock-Drills, of which the following description, in connection with the accompanying drawings, is a specification, like characters on the drawings representing like parts.

This invention relates to rock drills, being more particularly intended to provide an efficient but simple construction of drilling tool.

This application is a division of my prior co-pending application Serial No. 637,100, filed July 6, 1911.

The invention will be best understood by reference to the following description when taken in connection with the accompanying illustration of one specific embodiment thereof, submitted for illustrative purposes only, while its scope will be more particularly pointed out in the appended claims.

In the drawings:

Figure 1 is a plan view of a portion of a rock drill embodying one form of the invention;

Fig. 2 is an elevation in partial section of the construction shown in Fig. 1; and

Fig. 3 is a section in plan of a modified form of front head.

Referring to the drawings and to the embodiment of the invention there illustrated, I have shown the same embodied in a rock drill the cylinder whereof is shown at 1, the piston at 2, the latter being connected to a piston rod 3 adapted to carry at its outer end a chuck (not shown) for receiving the drill.

The front end of the cylinder is closed by a head of improved construction through which the piston rod passes. Referring to Figs. 1 and 2, the front head comprises a ring head 4, the upper end of which is frusto-conical and is counterbored to fit accurately the outside of the cylinder. The forward end of the cylinder is preferably turned on the outside to make it concentric with the bore and to receive the overlapping end of the ring head. Seated within the cone

shaped end of the ring head is a split bushing 5 which has a projection 6 of reduced diameter entering a counterbored portion of the cylinder. The forward end of the ring head is partially split and internally threaded, and is provided with a gland 7 in the form of a split bushing with stud joints. The opposing ends of the gland and bushing are beveled so that they tend to compress packing 8, which is clamped between them, against the piston rod 9. The outside diameter of the gland is slightly greater than the piston so that the latter can be passed through the ring head. The head can be packed by merely removing the gland and without unfastening the side rods of the drill. Both the bushing and the gland are bored accurately to fit the piston rod and, by means of the internal projection 6 on the bushing and the external projection on the ring head overlapping the cylinder, are kept in accurate alinement. These internal and external projections on the ring head which engage the cylinder act respectively as internal and external means for centering or alining the head with reference to the cylinder bore. They also serve to prevent leakage by providing an accurate metallic joint between the head and the cylinder.

The leakage, furthermore, is not only prevented by the overlapping shoulder on the ring head and the bushing, but also by a slight clearance 10 which is left between the bushing and the ring head. Any pressure fluid which leaks from the forward end of the cylinder tends to condense in this space and to form a water seal rendering leakage still more unlikely. The ring head, as shown in Fig. 1, is provided with side wings 11 which are perforated to receive the side rods 12, the latter being fastened in the front head by the nuts 13 and the intervening springs 14.

In Fig. 3 I have shown a slightly modified form of the front head, wherein the walls of the ring head are tapered throughout their full length and a single bushing 15 is provided having a packing 16 placed in a groove in said bushing. This form of front head, however, is also provided with internal and external centering projections similar to those shown in Fig. 2.

At their rear ends the side rods pass through lugs 17 on the cylinder and thus serve to clamp the front head 4 and rear head 18 together. I have found that much
5 breakage which occurs through the shock imparted to the side rods by the piston striking the front head can be avoided by equalizing the shock upon the two rods. For this purpose I have connected the side rods
10 by an equalizing device, herein consisting of an equalizing yoke bar 19 to the ends of which the side rods are bolted. The yoke bar has a curved inner face which rests against a preferably flat seat provided in
15 the end of the rear head between the lugs 20 so that it can rock slightly thereon and tend to equalize the unequal strains to which the side rods may be subjected, without in any way impairing their efficiency in
20 clamping the cylinder and heads together.

While I have herein shown and described for purposes of illustration one form of the invention, it is to be understood that the same is not limited to the details of construction
25 or the form or relative arrangement of parts or to the specific application of the invention, but that extensive deviations may be made therefrom without departing from the spirit of the invention.

30 Claims.

1. A rock drill having a front head comprising a ring, and an inner bushing having a clearance between the same and the ring to provide a water seal and having an inner
35 annularly disposed surface engageable with the end wall of a cylinder.

2. A rock drill having a front head comprising an internally grooved ring, and a flanged inner bushing having a clearance between the flange thereon and said groove
40

and having inner annularly disposed surfaces engageable with the end of a cylinder.

3. A rock drill having a front head comprising an internally grooved ring, a flanged inner bushing having a clearance between the 45 flange thereon and said groove, and a cylinder closing the end of said clearance and having a metal to metal contact with both said groove and said flange.

4. A rock drill having a cylinder, a front 50 head comprising an outer ring having a projection overlapping the outside of the cylinder, and an inner bushing having a projection entering the cylinder bore, a clearance being provided between the bushing and ring 55 to afford a water seal and said cylinder and front head presenting abutting faces in metallic contact.

5. In a rock drill, an outer head ring having a projection overlapping the outside 60 of the cylinder and an internally tapered portion, an inner bushing disposed in the tapered portion of said ring and coöperating therewith to form an annularly disposed clearance space between the latter and said projection, said bushing presenting a shou- 65 dered projection disposable in a cylinder bore, and a cylinder having its end wall engageable with a surface on said bushing and its inner and outer peripheries respectively 70 engaging the projection on said bushing and the projection on said ring.

In testimony whereof, I have signed my name to this specification in the presence of two subscribing witnesses.

GEORGE H. GILMAN.
